WINDOW LOCK

Steven J. Citso, Chicago, Ill.

Application July 19, 1947, Serial No. 762,141

6 Claims. (Cl. 292—175)

1

My invention is directed to self locking locks for window sash and other slidably mounted closure elements.

It is an important object of my invention to provide novel releasable window locks having spring pressed retractable latch bolts of the class described which are adapted to snap into locked position when the closure is moved into closed position and which have novel guard means actuatable upon closing movement to hold and releasably lock the slidable latch bolt into locked position.

A further object of my invention is the provision of self locking locks for slidable closures which have a novel combination of parts including an angular guard adapted to be moved and dropped over the latch bolt to prevent its unauthorized retraction and which is actuated to closing movement by movement of the locking element of the bolt into closed position; said guard being also adapted to limit the opening movement of the slidable sash.

Other and further important objects of my invention will be apparent from the following description and appended claims.

This invention, (in one preferred form) is illustrated in the accompanying drawing bearing numerals of reference contained in the accompanying specification.

Fig. 1 is a partially cross sectional and partially elevational enlarged view of my lock illustrating its mounting on adjoining sections of two window sash frames.

Fig. 2 is an enlarged cross section of the lock illustrating the lock bolt in retracted position.

Fig. 3 is a partially side elevational and partially cross sectional view, illustrating the lower sash frame in position upraised to the limit permitted by the guard of my device.

Fig. 4 is a cross sectional view taken on a plane indicated by line 4—4 of Fig. 3.

Referring to the drawings reference numeral 10 designates a lower slidable window sash frame whose outer edge face 10a is beveled as indicated, said face being adapted to engage a beveled face of the lower rail of an upper and outer sash frame 11. Said sash frames are illustrated as having fragments of glass panes 13 mounted therein in the usual manner.

As shown in cross section in Figs. 1 and 2 and in side elevation in Fig. 3, an elongated metal housing 12, having apertured laterally extending side flanges 14 and opposite apertured end walls 15 and 16, is secured against the upper flat face of the upper rail of sash frame 10 by a plurality

2

of screws 17, one of which is shown in Fig. 3. The end wall 16 has an enlarged preferably rectangular opening therein in which is slidably mounted a beveled stud 18 of slidable, retractable latch bolt 19. The upper face 20 of stud 18 is also slightly beveled toward its end as illustrated in Figs. 1 and 2. The handle 19a of latch bolt 19 is bent substantially at right angles as indicated in Figs. 1 and 2 and said bolt 19 carries an abutment member 19b. A compressible coil spring 21 is mounted about bolt 19 between wall 15 and stud 18 as shown in the drawing. A channel-like metal bracket 22 having oppositely extending apertured integral feet 23 is secured by screws 24 to the upper face of the upper rail of sash frame 11 as shown in Fig. 4. The opposite side portions of brackets 22 are apertured at their upper ends and a pin 25 is mounted therein, said pin passing thru aligned apertures 20 of ears 27 of trip lock 26 and forming a pivot for said trip lock. The hinged end portion of trip lock 26 is bent angularly and terminates in an edge face 26a. The free end portion of trip lock 26 is bent at right angles to form a stop element 26b to limit either the upward movement of the lower sash or downward movement of the upper sash, or part opening movements of both sashes.

Pivoted on the intermediate portion of bracket 22 by means of pivot 28 is a vertically slotted dog 27a whose projecting free end is reduced and beveled as shown in Figs. 1, 2 and 3. The slot 29 in dog 27a is wider than the thickness of the upwardly extending portion of a bendable, yieldable retaining member 30 whose lower angularly bent end is mounted in a transverse slot in the base of bracket 22 and impinged beneath an upwardly struck intermediate element 31 which is shown integral with the bracket base in Fig. 4. The face of the upper portion of yieldable retaining member 30 is adapted to frictionally engage the edge face 26a of trip lock 26 when said lock 26 is upraised position and such frictional engagement will normally hold said lock 26 in upper position when either sash frame is in partially open position.

When either the lower sash frame is lowered or the upper sash frame moved up, the lower beveled face of stud 18 will slidably engage the beveled edge of dog 27a to impart a slight downward movement to dog 27a, which in turn slightly bends the yieldable, retaining member 30 away from bracket 22 and away from pane 13. As the upper end of trip lock 26 is heavier (and its 55 lower edge face 26a being thereby released from

the engagement of retaining member 30) the said trip lock 26 will pivot and drop to the dotted line position shown in Fig. 1 so that the stop element 26b overlies the handle 19a of latch bolt 19 to prevent its being forced into open position by unauthorized manipulation.

When a person on the inside of the house desires to bring either of the sash frames towards each other (namely open either thereof) he will manually lift the trip lock 26 into upper position and retract bolt 19 from locking engagement and either pull the lower sash frame upwardly or the upper sash frame downwardly until the face 20 of stud 18 strikes the stop element 26b of trip lock 26 to thereby stop any further opening movement of either sash frame.

An important novel advantage of my construction and its operation is that no separate manual movement is necessary to place the trip lock 26 into locking position as this is automatically accomplished in the described manner upon the sliding of either or both sash frames into closed position.

When the user desires to fully open either sash frame, or both thereof beyond the limit normally permitted by stop element 26b the latch bolt 19 is withdrawn against the action of its spring and the stud 18 of bolt 19 will pass by or avoid engaging the stop element 26b as either sash frame is moved to a more than normal open position.

As many changes could be made in the above construction, and many apparently widely different embodiments of my invention, within the scope of the claims, constructed without departing from the spirit or scope thereof, it is intended that all matter contained in the accompanying specification shall be interpreted as illustrative and not in a limiting sense.

I claim:

1. In a self-locking latch for windows, a bracket secured to an upper sash frame; an angularly bent trip lock pivoted on said bracket; an apertured housing secured on the lower sash frame; a spring pressed latch bolt slidably mounted in said housing and having a stud at one end of said latch bolt; a slotted dog pivoted on said bracket; a bendable retaining member extending through said slotted dog, said retaining member in unbent position normally engaging an end of said trip lock when the window is open to thereby hold said trip lock in unlocked position, the closure of the window being adapted to cause engagement of said stud and said dog to cause said dog to pivot to thereby bend said retaining member to cause disengagement thereof from the end of said trip lock to thereby cause gravity pivoting of said trip lock into locking position.

2. In a safe-locking latch for windows, a bracket secured to an upper sash frame; an angularly bent trip lock pivoted on said bracket; a housing secured on a lower sash frame; a spring pressed latch bolt slidably mounted in said housing; a slotted dog pivoted on said bracket; a retaining member adjacent said bracket and extending upwardly through the slot of said dog, said retaining member being adapted to engage said trip lock to hold said trip lock in unlocked position, the engagement of said latch bolt and said dog during closure of the sash frames being adapted to cause movement of said retaining member from engagement with said trip lock to thereby permit said trip lock to pivot to locked position.

3. In a safe-locking latch for windows, a bracket mountable on an outer sash frame; a trip lock pivoted on said bracket; an apertured housing secured on an inner sash frame; a spring pressed latch bolt slidably mounted in said housing; a beveled stud on one end of said bolt; a slotted dog pivoted on said bracket; an upwardly extending retaining member extending through the slot of said dog and at selected positions of the sash frames engaging an end of said trip lock, at other positions of said sash frames said stud engaging said dog to cause downward movement of said dog to cause it to pivot to thereby cause movement of said retaining member from engagement with said trip lock to thereby permit gravity pivoting of said trip lock to locked position.

4. In a safety lock for window sash frames having an apertured housing on one of said sash frames; a slidable retractable bolt mounted in said housing and having a stud at one end; a spring for normally pressing said bolt into locking position; a bracket mountable on the other of said sash frames; a trip lock pivoted on said bracket and adapted when lowered to prevent retraction of said bolt; a slotted dog pivoted to said bracket; a yieldable retaining member on said bracket and extending upwardly through said slotted dog, said retaining member engaging said trip lock to hold said lock in upper position, the closing movement of a sash frame causing engagement of said stud and said dog to pivot said dog to thereby move said retaining member and disengage said trip lock and said retaining member to permit gravity pivoting of said trip lock upon said bolt, the further closing movement of a sash frame causing clearance of said dog and said stud to permit said stud to move outwardly to be retained from further opening movement by said dog until manual retraction of said bolt.

5. In a safety lock for window sash frames having a passaged housing and a retractable latch bolt slidable therein for one of said sash frames; a spring for moving said bolt into locking position; a bracket on the second sash frame; a trip lock pivoted on said bracket; a dog pivoted on said bracket and adapted to retain said latch bolt to lock said sash frames from movement; a retaining member engageable by said dog and normally holding said trip lock in open position; said bolt at selected positions coming into engagement with said dog to pivot same to cause disengagement of said retaining member and said trip lock to permit said trip lock to drop into latch bolt locking positions and prevent retraction of said latch bolt from unauthorized positions.

6. In a device for locking a slidable latch bolt against retraction; a bracket adapted to be secured on a slidable closure; a lock pivoted on said bracket and when lowered being adapted to lock a bolt against retraction; a retaining member normally applying pressure against said lock to retain it in open position; a dog pivoted on said bracket for locking a latch bolt; the movement into locking position of a latch bolt causing engagement thereof with said dog to pivot same to move said retaining member from engagement with said lock to permit said lock to move to locking position.
